UNITED STATES PATENT OFFICE.

ALBERT B. DISS, OF NEW YORK, N. Y.

CASTER.

SPECIFICATION forming part of Letters Patent No. 645,386, dated March 13, 1900.

Application filed May 15, 1899. Serial No. 716,798. (No model.)

To all whom it may concern:

Be it known that I, ALBERT B. DISS, a citizen of the United States, residing at New York, borough of Brooklyn, in the county of Kings 5 and State of New York, have invented an Improvement in Casters, of which the following is a specification.

Articles of furniture, especially bedsteads, have been made with tubular legs, usually of 10 iron pipes, with an ornamental surface of brass. These tubes are generally of considerable diameter and extend down closely to the place where the caster is attached. Difficulty has been experienced in connecting 15 the caster to the tube in a reliable manner, so that the caster can be easily detached and not be liable to injury in transportation and so that the caster can be taken off if it requires repairing. Efforts have been made to 20 connect the caster-pintle to the tube by intervening springs; but these are liable to injury, especially where the tube is of large diameter. In cases where disks have been made use of with spring edges the weight upon the 25 caster and the leverage of the caster and pintle against the spring-disk have been liable to injure the spring.

In the present invention the pintle is held in position within the tube by rigid disks, so 30 that there is no risk of injury by leverage or strain, and a spring is applied in such a manner as simply to afford the friction necessary to hold the caster within the tube and prevent the same dropping out if the bedstead-leg is 35 lifted; but this spring yields to allow the caster to be pulled out with facility when the bedstead is moved or transported, and such caster can be replaced with facility and will be held in position by the friction of the 40 spring, so that it cannot fall out.

In the drawings, Figure 1 is a vertical section representing the present improvement. Fig. 2 is a separate view of the spring which I prefer to use. Fig. 3 is a vertical section 45 representing a modification in the spring.

The caster-wheel A is supported in the jaws B, and these are connected to the vertical pintle C, and these parts are of any desired size or character, and the vertical pintle C 50 passes centrally through a disk D, which is sufficiently large for the lower end of the tubular leg E to rest upon such disk, and there

is a washer or disk F near the disk D, but of a size to pass into the inside of the tubular leg, and the second disk G is also of a size to 55 pass freely into the tubular leg, and it is advantageous to press up nibs or projections 2 upon the vertical pintle C to hold the disk G in position upon the pintle, but to allow the pintle to turn freely within the disk. 60

It will now be understood that the disks F and G cause the pintle to remain central within the tubular leg and that the pintle is free to turn within the respective disks and that lateral strain is taken upon the disks, and 65 these disks can be made of different sizes to suit the internal diameter of the tubular leg and that substantially the only thing which needs to be varied to suit different bedstead or other tubular legs is the diameter of the 70 disks that go into the inside of such tubular leg.

The parts which have already been described are all that are needed for a practically-operative caster; but in order to prevent 75 the caster dropping out if the bedstead is raised a friction-spring is applied that will act against the tubular leg and preferably within the same with a force sufficient to prevent the weight of the caster causing the same 80 to separate from the leg when the leg is raised. Any suitable friction device may be employed for this purpose. I, however, prefer and use the friction-spring H, which intervenes between the disks F and G. I find it advantageous to make this friction-spring with two 85 eyes 3 and 4, through which the pintle C passes, and these eyes serve to hold the spring in a definite position; but they do not apply to the spring a friction that interferes with 90 the freedom with which the pintle can be turned with the caster while in use.

In Figs. 1 and 2 the eyes 3 and 4 are represented as connected together by a band 5, and this band can be bent into any desired 95 shape so that the eyes 3 and 4 can be at any desired distances apart, and the arms 6 extend out from the band 5 or eyes and are provided at their ends with the springs H, and these parts all being of sheet metal can be bent up 100 into the desired shapes so that the ends of the springs bear against the interior of the tubular leg, as represented in Fig. 1. The springs H' may be upon a cross-arm 7, hav-

ing through it a hole for the passage of the pintle C, and the springs H' extend up from the outer ends of the arms 7 and are bent of the proper shape to apply friction against 5 the interior surface of the tubular leg; and it is advantageous to notch the edges of the disk D at places where the arms 7 pass by the same; but, if desired, the friction-spring may be entirely between the disks F and G, 10 in which case such disks F and G can be circular at the edges and without notches. The spring H' is represented in Fig. 3.

Where the spring is made with eyes, as 15 shown in Fig. 1, such eyes and the connecting-band regulate the distances between the disks F and G, and in that case it is only necessary to press up the lugs or teats 2 upon the vertical pintle and above the upper disk G to retain the same in position, as illustrated in Fig. 1; but where the spring is connected by a single cross-piece, as in Fig. 3, it is advantageous to press up lugs or teats 20 upon the pintle below the disk G as well as above the same.

25 I claim as my invention—

1. The combination with the caster-wheel, jaws, pintle and bottom plate or disk, of two independent disks perforated for the passage of the pintle, the disks passing into and corresponding substantially with the interior 30 diameter of the tubular leg, means for holding and securing the disks in position to and directly upon the pintle, and a spring acting between the disks and connected to the pintle for applying friction within the tubular leg to hold the caster to such leg, substantially as set forth.

35 2. The combination with the caster-wheel, jaws, pintle and bottom plate or disk, of two

independent disks perforated for the passage 40 of the pintle, the disks passing into and corresponding substantially with the interior diameter of the tubular leg, means for holding the disks in position to and directly upon the pintle and a band and eyes surrounding the pintle and intervening between the disks to determine the distance between such disks, substantially as set forth.

3. The combination with the caster-wheel, jaws, pintle and bottom plate or disk, of two 45 independent disks perforated for the passage of the pintle, the disks passing into and corresponding substantially with the interior diameter of the tubular leg, means for holding the disks in position to and directly upon the 50 pintle, central transverse arms extending across the pintle and springs carried by such arms for applying friction to hold the caster in position upon the leg, substantially as set forth.

4. The combination with the caster-wheel, jaws and pintle, of a plate surrounding the pintle and upon which the tubular leg rests, disks or supports perforated for the passage 55 of the pintle and passing into the tubular leg, and means for holding such disks or supports in position, eyes surrounding the pintle and a connecting-plate between the eyes and between the upper and lower disks and a spring supported by such eyes and acting 70 to apply a friction within the tubular leg to hold the caster in position, substantially as set forth.

Signed by me this 12th day of May, 1899.
ALBERT B. DISS.
